UNITED STATES PATENT OFFICE.

EDWARD G. BUDD, OF PHILADELPHIA, PENNSYLVANIA, ASSIGNOR TO
HALE-KILBURN METAL COMPANY, OF PHILADELPHIA, PENNSYLVANIA, A CORPORATION OF PENNSYLVANIA.

DESIGN FOR A SEAT END.

No. 38,217.

Specification for Design.

Patented Aug. 28, 1906.

Application filed July 18, 1906. Serial No. 326,792. Term of patent 7 years.

To all whom it may concern:

Be it known that I, EDWARD G. BUDD, a citizen of the United States, residing at Philadelphia, in the county of Philadelphia and State of Pennsylvania, have invented a new, original, and ornamental Design for Seat Ends, of which the following is a specification, reference being had to the accompanying drawing, forming part hereof.

The figure is a plan view of a seat end embodying my new design.

I claim—

The ornamental design for a seat end as shown.

EDWARD G. BUDD.
